CLAIM

I claim the ornamental design for a simulated shake panel, as shown and described.

DESCRIPTION

FIG. 1 is a top plan view of a simulated shake panel.

FIG. 2 is a fragmentary and enlarged front elevation view of a simulated shake panel of FIG. 1.

FIG. 3 is a bottom plan view of a simulated shake panel of FIG. 1.

FIG. 4 is a fragmentary and enlarged bottom plan view a simulated shake panel of FIG. 1.

FIG. 5 is a front elevation view of a simulated shake panel of FIG. 1.

FIG. 6 is a fragmentary and enlarged front elevation view of a simulated shake panel of FIG. 1.

FIG. 7 is a rear elevation view of a simulated shake panel of FIG. 1.

FIG. 8 is a fragmentary and enlarged rear elevation view of a simulated shake panel of FIG. 1.

FIG. 9 is a right end elevation view of a simulated shake panel of FIG. 1.

FIG. 10 is a left end elevation view of a simulated shake panel of FIG. 1.

FIG. 11 is a fragmentary and enlarged right end perspective view of a simulated shake panel of FIG. 1; and,

FIG. 12 is a fragmentary and enlarged left end perspective view of a simulated shake panel of FIG. 1.

The broken lines showing a wood-like texture represents environmental structure which form no part of the claimed design.

The broken lines showing a boundary at the cut portion of the fragmentary views of FIGS. 2, 4, 6, 8, 11 and 12 are not intended to form part of the claimed design. A boundary at such broken lines does not exist in reality in the article

(Continued)

embodying the design. It will be understood that the claimed design extends to the boundary at the broken lines but does not include such boundary.
